Primary Examiner — Sheryl Lane*Assistant Examiner* — Nicole Shiflet(74) *Attorney, Agent, or Firm* — Rutan & Tucker, LLP**CLAIM**

The ornamental design for a catheter, as shown and described.

DESCRIPTIONFIG. 1 is a top perspective view of a catheter;
FIG. 2 is a bottom perspective view of the catheter illustrated in FIG. 1;FIG. 3 is a top view of the catheter illustrated in FIG. 1;
FIG. 4 is a bottom view of the catheter illustrated in FIG. 1;
FIG. 5 is a first side view of the catheter illustrated in FIG. 1;
FIG. 6 is a second side view of the catheter illustrated in FIG. 1;
FIG. 7 is a front view of the catheter illustrated in FIG. 1; and,
FIG. 8 is a rear view of the catheter illustrated in FIG. 1.

The broken lines in the figure drawings represent portions of the article and form no part of the claimed design.
